CLAIM

The ornamental design for a mounting bracket, as shown and described.

DESCRIPTION

FIG. 1 is a bottom-left front perspective view of a mounting bracket showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a bottom plan view thereof;

FIG. 7 is a top plan view thereof; and,

FIG. 8 is a cross-section view thereof, taken along line 8-8 of FIG. 2.

The dashed broken lines represent unclaimed portions of the article and form no part of the claimed design. The dash-dot-dot lines indicate a boundary of the claim.

1 Claim, 8 Drawing Sheets(56)
